(57) **CLAIM**

The ornamental design for a relay replacement assembly, substantially as shown and described.

DESCRIPTION

FIG. 1 is a back, right side, and top perspective view of a relay replacement assembly;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof;

FIG. 8 is a front, left side and top perspective view;

FIG. 9 is a back, left side and top perspective view, shown in a state of use; and,

FIG. 10 is a front, left side, and top perspective view, shown in a state of use.

The broken lines in the drawings are for the purpose of illustrating environmental subject matter and form no part of the claimed design.
